UNITED STATES PATENT OFFICE

109,026

DESIGN FOR A BUILDING

Carl A. Petersen, Chicago, Ill.

Application December 16, 1937, Serial No. 73,657

Term of patent 14 years

To all whom it may concern:

Be it known that I, Carl A. Petersen, a citizen of the United States, residing at Chicago, in the county of Cook and State of Illinois, have invented a new, original, and ornamental Design for a Building, of which the following is a specification, reference being had to the accompanying drawings, forming part thereof.

Fig. 1 is a front elevational view of a building showing my new design;

Fig. 2 is a side elevational view; and

Fig. 3 is a perspective view of the front and side thereof.

The rear wall of the building is straight and plain and contains no windows. The rear view of the roof corresponds substantially to the front view thereof.

I claim:

The ornamental design for a building, as shown and described.

CARL A. PETERSEN.
